[57] CLAIM

The ornamental design for a decorative frame, as shown and described.

DESCRIPTION

Reference is made to the following six design patent applications which are filed on even date herewith which also claim decorative frames: (1) U.S. Ser. No. 29/095,616 (Attorney Ref: 321.850D00); (2) U.S. Ser. No. 29/095,618 (Attorney Ref: 321.852D00); (3) U.S. Ser. No. 29/095,617 (Attorney Ref: 321.853D00); (4) U.S. Ser. No. 29/095,653 (Attorney Ref: 321.854D00); (5) U.S. Ser. No. 29/095,654 (Attorney Ref: 321.855D00); and (6) U.S. Ser. No. 29/095,655 (Attorney Ref: 321.856D00).

FIG. 1 is a front view of the invention;

FIG. 2 is a rear view of the invention;

FIG. 3 is a top view of the invention;

FIG. 4 is a bottom view of the invention;

FIG. 5 is a left side view of the invention; and,

FIG. 6 is a right side view of the invention.

Unclaimed subject matter is shown in dotted line format.
